UNITED STATES PATENT OFFICE.

OSCAR DELLWITZ, OF TEGEL, NEAR BERLIN, GERMANY.

ROLLING-MACHINE.

1,141,447.

Specification of Letters Patent.

Patented June 1, 1915.

Application filed December 29, 1914. Serial No. 879,588.

To all whom it may concern:

Be it known that I, OSCAR DELLWITZ, a subject of the German Emperor, and resident in Tegel, near Berlin, Germany, have 5 invented certain new and useful Improvements in Rolling-Machines, of which the following is a specification.

This invention relates to pilgering mills and has for its object a suitable device for 10 bringing the work and mandrel into the starting position without shock. For this purpose the mandrel is mounted upon a hollow piston, of two different diameters, working in a cylinder to which compressed air, 15 gas or the like is supplied. The reduced portion of the piston is provided with apertures, of which the area may be varied, through which the compressed air passes into the space between the reduced portion of the 20 piston and cylinder where the air is still more compressed acting as a cushion and finally bringing the piston and work to rest without shock.

In the accompanying drawing is illustrated 25 a longitudinal section of a rolling machine constructed according to the present invention.

In the drawing, *f* are the rolls which are rotated continuously in the direction of the 30 arrows *x*; *g* indicates the work and *h* the mandrel on which the work is rolled and extended. The rear end of the mandrel is mounted in a hollow piston *b*, of two different diameters, working in a cylinder *a*. The 35 latter is supported by a saddle (not shown in the drawing), which feeds the mandrel and work as the rolling process progresses toward the rolls. The rear end of the piston *b*, is open so that compressed air or any 40 other analogous medium can be supplied at determined intervals to the interior of the piston through the port in the cylinder head *i*. The compressed air passes from the interior of the piston *b* through apertures *c* 45 into the space between the reduced portion of the piston and the cylinder *a*.

In the position shown, it is assumed that the cylinder and the hollow piston are both 50 completely filled with compressed air so that the piston will move in the direction of the arrow *y*. When the piston has nearly completed its stroke, the apertures *c* are gradually closed by a sleeve or socket *d* mounted in the forward end of the cylinder. 55 Compressed air will then be trapped between the piston and cylinder, this air being still

further compressed on the forward movement of the piston so that the speed of the latter is reduced and the piston finally brought to rest. When the energy of the 60 moving piston has been absorbed, the highly compressed air between the reduced portion of the piston and the cylinder after bringing the piston and work to rest will cause a recoil in the reverse direction.

In order to be able to increase or decrease this recoil with certainty as desired without shock, the apertures *c* may be enlarged or reduced in length and breadth by means of a sleeve *e* provided with similar openings 70 and movably mounted in the reduced portion of the piston, the position of the sleeve *e* controlling the passage of air from the reduced portion of the piston into the space between the piston and the cylinder.

Having thus described my invention, what I claim as new and desire to secure by Letters Patent is:—

1. In a pilgering mill, the combination comprising a cylinder adapted to be supplied with a compressed fluid, a piston mounted within said cylinder and adapted to leave a hollow space between a portion of said piston and the forward end of the cylinder, said piston having means of communication with the hollow space and being adapted in its movement to close said means of communication so as to form a cushion, and a mandrel mounted in said piston.

2. In a pilgering mill, the combination comprising a cylinder adapted to be supplied with a compressed fluid at its rear end, a hollow piston mounted in said cylinder, the rear end of the piston being open and communicating with the cylinder, said piston being so arranged in the cylinder as to form a hollow space between a projecting part of the piston and the forward end of the cylinder, said piston having means of communication with said hollow space, and being adapted on its movement to close said means of communication so as to form a cushion, and a mandrel mounted in the forward end of said piston.

3. In a pilgering mill, the combination comprising a cylinder adapted to be supplied with a compressed fluid, a hollow piston in said cylinder having a reduced portion adapted to pass through the forward end of the cylinder and forming a hollow space around said reduced portion, said reduced portion having means of communica-

tion between the interior of the hollow piston and the hollow space, the piston in its movement being adapted to close said means of communication so as to form a cushion, and a mandrel mounted in the reduced portion of the piston.

4. In a pilgering mill, the combination comprising a cylinder adapted to be supplied with a compressed fluid, a hollow piston in said cylinder, having a reduced portion adapted to pass through the forward end of the cylinder and forming a hollow space around said reduced portion, said reduced portion having means of communication between the interior of the hollow piston and the hollow space, the piston in its movement being adapted to close said means of communication so as to form a cushion, a sleeve having apertures mounted in the reduced portion of the piston, said sleeve being capable of adjustment to vary the cross section of said means of communication, and a mandrel mounted in the reduced portion of the piston.

5. In a pilgering mill, the combination comprising a cylinder adapted to be sup-

plied with a compressed fluid, a hollow piston in said cylinder, having a reduced portion adapted to pass through the forward end of the cylinder and forming a hollow space around said reduced portion, said reduced portion having means of communication between the interior of the hollow piston and the hollow space, the piston in its movement being adapted to close said means of communication so as to form a cushion, 25 a sleeve having apertures mounted in the reduced portion of the piston, said sleeve 30 being capable of adjustment to vary the cross section of said means of communication, and a mandrel mounted in the reduced portion of the piston.

In testimony whereof, I affix my signature, in presence of two witnesses.

OSCAR DELIWITZ.
